BINDER AND MOUNTING STRUCTURE FOR
CATALOGUES OR THE LIKE

Thomas M. Dunham, Aurora, Ill.

Application December 31, 1936, Serial No. 118,487

8 Claims. (Cl. 129—1)

This invention relates to improved binder and mounting structure for catalogues, directories, loose leaves, or the like, the invention covering particularly improved binder units and improved 5 means adaptable for securing together the component parts of the binder units and also for detachably securing the binder units to a mounting board or panel.

An important object of the invention is to provide 10 binder units composed of similar halves of sheet metal provided with means for receiving and binding catalogues, loose leaves, or the like, with the halves at their ends having registering perforations for receiving individual spring clips 15 for detachably securing the halves together.

A further object is to provide a mounting in 20 the form of a board or panel, preferably of sheet metal, having rows of perforations for registering with the perforations in the binder units and 25 through which perforations the clips may be extended so that the clips may serve also to detachably secure the binder units to the mounting.

A further object is to provide improved clips, 30 preferably formed of spring wire, with a tongue thereon for insertion through the binder unit perforations for securing the binder component parts together when the binder is removed from the mounting, or to be extended through the mounting perforations or apertures for detachably securing the binder units with their contents to the mounting boards.

The various features of the invention are incorporated in the structure disclosed on the drawing, in which drawing:

35 Figure 1 is a plan view of the mounting structure with a number of binder units mounted thereon;

Figure 2 is an enlarged section on plane II—II of Figure 1;

40 Figure 3 is an enlarged section on plane III—III of Figure 1;

Figure 4 is a plan view of the spring clip;

Figure 5 is a side view of the spring clip;

45 Figure 6 is a section on plane VI—VI of Figure 4;

Figure 7 is an enlarged longitudinal section of a binder unit showing how the parts thereof are secured together by the clips; and

50 Figure 8 is an enlarged section showing the clips applied to secure a unit to the mounting panel.

The mounting board or panel 10 is preferably in the form of a sheet metal plate having strengthening longitudinal and end flanges 11 55 and 12 respectively. The panel has a longitudinal row of perforations or apertures 13 adjacent to its upper margin and a similar row of apertures 14 along its lower margin, the openings in the upper and lower rows being in transverse 60 alignment.

The binder units shown comprise each substantially similar halves preferably of sheet metal, each half comprising a side strip or wall 15 and a flange or base 16 extending at right angles on the lower edge thereof, and the flanging may be continuous or provided only along the end portions of the side walls. The side walls are provided with posts 17 for receiving the perforations of catalogues, loose leaves or the like when the unit halves are assembled with 10 their flanging ends in overlapping engagement.

The flanging near the end of each side wall has perforations 18 and 19 respectively, and when the flangings of two side walls are overlapped, these apertures at the ends of the unit will be 15 in registration, and the longitudinal distance between the apertures at the ends of the unit is equal to the distance between the aperture rows 13 and 14 of the mounting panel 10.

As a simple, effective, and efficient means for 20 detachably securing the halves of a unit in binding relationship, I have provided individual clips C, each of which may be bent up from a single length of spring wire. As shown, the clip comprises an oblong or rectangular body 20 formed from the intermediate portion of a length of wire, the end portion of the wire length forming a tongue 21 extending from one end wall of the body 20 longitudinally of the body and with the ends 21' extending a distance beyond the opposite end of the body. Near the end of the body from which the tongue part extends, the body and the tongue part is deflected downwardly as indicated at 22 to form the inclined ends 23 which serve as a finger hold to assist in applying or withdrawing the clip. Between the deflected portion 22 and the end of the tongue, the tongue is deflected downwardly a distance below the plane of the body part 20 as indicated at 24, the tongue end 21' normally engaging the 40 under side of the adjacent body end wall 20' and being inclined downwardly therefrom.

After a number of catalogues, loose leaves or the like, which are to be bound, have been received on the posts 17 of a binder unit, the flanging apertures 18 and 19 at the upper and lower ends of the unit are in registration and clips are inserted in these registering apertures to detachably secure the binder halves together. As shown by dotted lines in Figure 7, the projecting end 21' of the clip tongue is inserted 45 through the registering apertures while the clip is slightly inclined, and then longitudinal pressure is applied to the clip with the result that the end of the tongue beyond the deflection 24 will be spring pressed against the under side of the unit and the body 20 will be spring pressed 50 flat against the inner side of the overlapping flanging of the unit, and the unit halves are thus 55 detachably locked together, as shown by the full 60

lines in Figure 7. To remove the clips, the thumb or finger is applied under the deflected end 23 of the clip body, and a combined upward lift and outward pull on the clip will readily withdraw the clip from the aperture.

As clearly shown by Figures 1, 3, and 8, the clips also function to secure the binder units to the mounting panel 10. After loading of a binder unit, it is placed transversely on the panel with its upper and lower registering flange perforations 18 and 19 respectively coinciding with a set of upper and lower apertures 13 and 14 in the panel and then the spring clips are inserted through the registering apertures with the tongues thereof spring pressed against the under side of the panel and the body thereof spring pressed against the binder unit so that the units will be detachably secured to the panel. The panel may be of a length for receiving any desired number of binder units, the panel perforations being properly spaced longitudinally so that there will be plenty of clearance between the units. When additional material is to be added to any of the binders, the binder can be readily removed by withdrawing the spring clips, and the binder can be as readily reapplied to the mounting panel.

Being of comparatively light sheet metal, the panel with the binder unit thereon may be readily carried about from place to place, or the panel may be supported or secured to form the top of a supporting stand or cabinet, and may be secured either in horizontal position or in inclined position, the inclined longitudinal flanges 11 adapting the panel for such inclined position.

I have shown a practical and efficient embodiment of the features of my invention, but I do not desire to be limited to the exact structure and arrangement shown as changes and modifications are possible which would still come within the scope of the invention.

I claim as follows:

1. In a structure of the class described, a supporting base having transversely spaced apart rows of apertures, binder strips having means for securing between them books or loose leaves to be bound together, overlapping flanges at the lower edges of said strips, the overlapping flanges at each edge having registering apertures for registration with an aperture of one of said base rows of apertures, and a spring clip element at each end of the binder structure engaging through the aligned apertures for detachably securing the binder structure to the base.

2. Binding and mounting structure for catalogues, loose leaves or the like, comprising binder units and a mounting base therefor, each binder unit comprising side plates having means for securing therebetween catalogues or loose leaves to be bound, said side plates having extensions in overlapping engagement and provided with registering apertures, said base having apertures for registration with the binder unit apertures, and means in the form of individual spring clips for engagement in the aligned apertures for detachably securing the binder unit parts together and for detachably securing the units to the mounting base.

3. In binder and mounting structure for catalogues, loose leaves or the like, a binder unit comprising side plates having means for securing therebetween catalogues, loose leaves, or the like to be bound, flanges at the outer portions of said

side plates extending inwardly from the outer edges thereof for overlapping engagement and having apertures adapted to register, individual spring clips each comprising a body portion and a tongue thereon, the tongues of said clips being insertable through the aligned perforations for holding said side plates in binding position, and a mounting base having apertures in registration with the apertures of the binder unit through which base apertures the tongues of said clips are extended so that said clips serve also to detachably secure the binder unit to said base.

4. Binder and mounting structure for catalogues, loose leaves or the like comprising binder units and a mounting base therefor, each binder unit comprising like halves of L-shaped cross section, means on the vertical walls of the unit halves for receiving and supporting the catalogues or the like to be bound, the horizontal walls of the unit halves overlapping and having registering apertures, said mounting base having apertures for registration with the binder unit apertures, and means in the form of individual spring clips engageable in the aligned apertures for locking the halves of the binder units together and for detachably securing the units to the base.

5. Binding and mounting structure for catalogues, loose leaves or the like, comprising binder units and a mounting base therefor, each binder unit comprising side plates having means for securing therebetween catalogues or loose leaves to be bound, said side plates having extensions in overlapping engagement and provided with registering apertures, said base having apertures in registration with the binder unit apertures, and fastening means for engagement in the aligned apertures for detachably securing the binder unit parts together and for detachably securing the units to the mounting base.

6. In a structure of the class described, a base having perforations, a binder comprising component parts adapted when assembled to bind together catalogs, loose leaves or the like, said binder component parts having perforations for registering with perforations of said base, and detachable spring clips extending through the registering perforations for detachably securing the binder to the base, said clips when detached from said base serving to secure the binder component parts together.

7. In a structure of the class described, a binder supporting base, a binder comprising component parts adapted when assembled to bind catalogs, loose leaves or the like, said component parts having registering apertures, individual spring clips having tongues extending through registering apertures whereby to clamp said component parts together, said base having apertures for receiving said tongues whereby said clips will also serve to detachably clamp the binder to the base.

8. In a structure of the class described, a base having perforations, a binder comprising component parts adapted when assembled to bind together catalogs, loose leaves or the like, said binder component parts having perforations for registering with perforations of said base, and securing members extending through the registering perforations for detachably securing the binder to the base, said securing members when detached from said base serving to secure the binder component parts together.
